UNITED STATES PATENT OFFICE.

CARL H. KNUDSEN, OF BROOKLYN, NEW YORK, ASSIGNOR TO THE KNUDSEN MOTOR CORPORATION, OF WILMINGTON, DELAWARE, A CORPORATION OF DELAWARE.

FUEL PUMP.

Application filed July 24, 1923, Serial No. 653,432. Renewed April 1, 1927.

This invention relates to fuel pumps and particularly to pumps of this class designed for use in pumping fuel oil to the spray nozzles of internal combustion engines, as well as to the provision of improved means for automatically governing the pump action; and the object of the invention is to provide a pump mechanism of the class specified whereby a predetermined fuel charge at a predetermined pressure may be supplied to the spray nozzle or nozzles of a motor proportionately to the speed of the motor, said pump mechanism being controlled by an automatically actuated governor device; a further object being to provide means for regulating or adjusting the action of the governor to control and regulate the fuel feed to the spray nozzle or nozzles of a motor; a further object being to provide improved means involving levers and cranks for actuating the pump or pump rod or rods of the mechanism to provide a simple and yet positive operation thereof, and to regulate the throw of the pump rod or rods through said governor mechanism; and with these and other objects in view, the invention consists in a fuel pump mechanism of the class and for the purpose specified, which is simple in construction and operation, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a sectional view through my improved pump mechanism showing certain operative parts thereof, the section being on the line 1—1 of Fig. 2 of the drawing.

Fig. 2 is a partial section on the line 2—2 of Fig. 1.

Fig. 3 is a partial section on the line 3—3 of Fig. 1.

Fig. 4 is a partial section on the line 4—4 of Fig. 2; and,

Fig. 5 is a partial section on the line 5—5 of Fig. 4.

In the construction shown I provide a frame or casing 10 which may be of any desired height and which is of box-shaped formation, said casing being provided with a bearing portion 11, in which is mounted a

bearing 12 for a shaft 13. The shaft 13 extends longitudinally through the casing and is provided at its free end with a flange 14 keyed or otherwise formed integrally therewith. The flange 14 facilitates the coupling of a motor shaft 15 indicated in dotted lines 55 in Figs. 2 and 4 of the drawing with the shaft 13, and the motor shaft 15 extends through an aperture 16 in the casing 10.

The top of the casing 10 is open and closed by two cover members 17 and 18, the cover member 17 being provided with a projection 19 upon which is mounted a pump body 20 held in place by screws or bolts 21. Formed in the cover member 17 and casing 10 is a large rib or web structure 22 clearly shown in Fig. 1 of the drawing, and in the cover member 17 is another rib or web structure 23, and the cover member 17 and casing 10 are provided with other bosses 24, in which a bell-crank 25 is pivotally mounted.

Keyed to the shaft 13 is a cam 26 which in the construction shown is provided with two grooved cam faces 27 oppositely arranged on said cam as clearly shown in Fig. 2 of the drawing. Pivotally mounted in the web structure 22 and cover member 17 is a shaft 28 on which is pivotally mounted two arms 29, the free ends of which are yoke-shaped in form to receive and support rollers 30 which bear upon the cam 26 and are adapted to operate in the cam grooves 27. The upper faces of the arms 29 are grooved as shown at 31 in Fig. 2 of the drawing and rollers 32 mounted in connection with the free end portions of arms 33 are adapted to operate in the grooves 31. The arms 33 are pivotally mounted in connection with independent extensions of a rocker arm 34 as clearly shown in Figs. 1 and 4 of the drawing, said rocker arm being mounted on a shaft 35 between the adjacent faces of the casing and cover member 17 and in the web structure 22.

To the other end of the rocker arm 34 is pivotally mounted an adjustable rod 36 which is pivotally mounted to an arm 37 of the bell-crank 25. Another arm 38 of said bell-crank is provided with a coil spring 39, the other end of which is coupled with an adjustment screw 40, whereby the tension of the spring 39 may be regulated, and said bell-crank is also provided with a yoke-shaped arm 41 having rounded end portions 42 adapted to bear upon a bearing 43 on a sliding sleeve 44 mov-

able longitudinally of the shaft 13. Pivot to the sleeve 44 are two or more governor weights 45 held in normal position by light springs 46, and the weights 45 are provided with outwardly directed finger pieces 47 adapted to operate in an annular groove 48 formed in a tubular extension 49 secured to or forming a part of the flange 14 as clearly shown in Fig. 2 of the drawing.

10 Mounted in the cover member 17 and the web portion 23 thereof is a rod 50 on which is mounted two arms 51 which extend over and operate in connection with the rollers 32 as clearly shown in Figs. 1 and 4 of the drawing.

15 A part of the extension 19 of the cover member 17 is made hollow as shown at 52 and the remaining structure is drilled to form an aperture 53, with which the fuel supply pipe 54 is coupled and is also drilled at right angles to 20 form a passage 55 in communication with the passage 53. At spaced intervals, the extension 19 is drilled vertically to form passages 56 communicating with the passage 55, and then horizontally to form other passages 57 25 in communication with the passages 56 and controlled by a ball-check 58, and the enlargement 19 is again drilled vertically to form passages 59 in communication with the passages 57. Mounted in the pump body are 30 two sleeves 60 which are counter-bored and provided with two check-valves 61 and the sleeves 60 are held in place by screws 62, the lower ends of which are apertured to place the bores of the sleeves 60 in communication with horizontal bores 63 in the 35 pump body 20 as clearly shown in Fig. 1 of the drawing.

40 Mounted in the pump body are sleeve guides 64, in which pump rods 65 are slidably mounted, said rods being grooved to form an oil seal where they slide in the sleeve 64 and extend below said sleeve and are provided at their free ends with collars 66 forming spring seats for conical spiral springs 67 which normally 45 hold the rounded conical ends 68 of the pump rods 65 in engagement with the top faces of the arms 51. The other ends of the pump rods 65 extend upwardly into pump chambers 69, with which the passages 63 communicate, and 50 suitable strainer devices are employed to strain the fuel oil as it enters the pump chambers 69. Mounted in the pump body 20 above the pump chambers 69 are tubular plugs 71 in which are mounted check-valves 72, and at 73 55 are couplings for attaching feed pipes 74 with the sleeve plugs 71, and these feed pipes extend to the spray nozzles of the motor in the usual manner.

60 The operation of my fuel pump will be readily understood from the foregoing description when taken in connection with the accompanying drawings and following statement. Fuel oil is first fed into the pump chambers 69 in the pump body 20 through 65 the pipe 54 and the bores 56, 57 and 63 and

through the sleeves 60 in this operation, through the pump chambers 69 and feed pipes 74 to the nozzles of the motor, and when all of these bores, feed pipes and the like are filled the motor will be ready for starting and the 70 pump put into action. As the motor shaft 15 which is indicated in dotted lines in the drawing rotates, the shaft 13 with the cam 26 thereon as well as the sleeve 44 is correspondingly rotated, thus bringing the governor device comprising the sleeve 44 and governor weights 45 into action and causing the sleeves 44 to be moved inwardly and longitudinally of the shaft 13, which operation will 75 rock the bell-crank 25 through the yoke-head 41, and the rocking of the bell-crank 25 will correspondingly operate the arm 37 thereof, and through the adjustable rod 36 the rocker arm 34 is actuated, thus imparting a sliding movement to the arms 33 carrying the rollers 80 32. The action of the cam 28 or the cam grooves 27 thereof will intermittently permit the arms 29 and rollers 30 thereof to drop into said cam grooves, thus lowering the arms 29, 33 85 and 51, and the pump rods 65 are correspondingly moved downwardly by the springs 67, allowing additional fuel oil to enter the fuel chamber 69 to take up for the rod displacement in said chamber, and as the cam continues to rotate, the arms 29, 33 and 51 are again 90 raised and the pump rod 65 correspondingly raised, in which operation the check-valves 61 and 58 are closed and the fuel oil in the pump chambers 69 is forced under pressure 95 through the feed pipes 74 to force or spray the oil from the nozzles on the motor in the usual manner, and it will be understood that the 100 above operation is intermittently performed in the separate pump chambers 69 and through the feed pipes 74 to separate and independent spray nozzles, and while I have shown and described but two pump rods and the various parts cooperating therewith, one or more of these may be employed, and it is preferred that a single pump unit, comprising 105 the pump rod 65, pump chamber 69 and feed pipes 74 be employed for each spray nozzle, but this is not absolutely essential.

110 From the foregoing, it will also be apparent that as the speed of the motor increases, the governor weights 45 are moved outwardly by centrifugal force against the tension of the springs 46 as well as the tension of the spring 39, which controls the action of said governors, and the ratio of movement or travel of 115 the pump rods 65 is automatically regulated; that is to say, the movement of said rods is increased in the increased revolutions of the motor and decreased as the motor speed decreases. By adjusting the screw 40, the tension on the governor weights 45 may be regulated to regulate the volume of fuel charged 120 into the motor, while the cam 26 or the grooves 27 therein control the rapidity of the action of the pump rods by reason of their 125 130

mounting on the shaft 13, which is coupled with the motor shaft 15.

In brief, the action of my improved fuel pump consists simply in the downward intermittent movement of the pump rods to admit additional fuel oil into the fuel chambers, and to force the said additional fuel into a fuel spray nozzle in the operation of the motor, means being employed to regulate and adjust the throw and the ratio of the throw, and this is accomplished through the adjustment provided in the rod 36, which will regulate the relative position of the rollers 32 on the arms 29 and 51, as does the position of the rollers 32 which control the ratio of movement imparted to the rods 65 by the cam 26 or the cam faces 27 thereof and not by the depth of said cam faces or grooves.

It will be understood that while I have shown certain details of construction for carrying my invention into effect, that I am not necessarily limited to these details, and various changes therein and modifications thereof may be made within the scope of the appended claims without departing from the spirit of my invention or sacrificing its advantages.

Having fully described my invention, what I claim as new and desire to secure by Letters Patent, is:—

1. In a pump of the class described employing a pump element, means involving two levers having substantially oppositely disposed fulcrums and a reciprocating lever positioned therebetween, whereby the operation of one of the first named levers will impart to the other of said first named levers and said pump element, direct increased or decreased strokes governed by the position of the reciprocating lever with reference to the first named levers.

2. In a pump of the class described comprising a pump element and cam, a plurality of levers disposed between said cam and said element, one of said levers being directly operated by said cam, another of said levers operating directly in connection with said element, said last named levers having substantially oppositely disposed fulcrums and extending in substantially parallel relation, and the other of said levers being disposed between the first named levers and adapted to control and regulate the direct increase or decrease movement imparted to said element through said levers and said cam.

3. In a pump of the class described comprising a pump element and cam, a plurality of levers disposed between said cam and said element, one of said levers being directly operated by said cam, another of said levers operating directly in connection with said element, said last named levers having substantially oppositely disposed fulcrums and extending in substantially parallel relation, and the other of said levers being disposed

between the first named levers and adapted to control and regulate the direct increase or decrease movement imparted to said element through said levers and said cam, and means involving a governor for controlling the action of said last named lever.

4. In a pump of the class described comprising a pump element and cam, a plurality of levers disposed between said cam and said element, one of said levers being directly operated by said cam, another of said levers operating directly in connection with said element, said last named levers having substantially oppositely disposed fulcrums and extending in substantially parallel relation, and the other of said levers being disposed between the first named levers and adapted to control and regulate the direct increase or decrease movement imparted to said element through said levers and said cam, means involving a governor for controlling the action of said last named lever, and tensional means for normally holding said element in engagement with the second named lever.

5. A pump mechanism of the class described comprising a pump body in which is formed a pump chamber, a plunger mounted in said body and extending into said chamber, means involving a cam for normally retaining said plunger in a raised position, a plurality of levers disposed between said cam and said plunger, two of said levers having substantially oppositely disposed fulcrums, and the other of said levers being disposed between the first named levers and adapted to control and regulate the movement imparted to said plunger, and means involving said cam and levers for permitting sudden downward movement of the plunger to admit oil into said chamber and for successively moving the plunger upwardly to displace the oil previously admitted into said chamber in the downward movement of said plunger.

6. A pump mechanism for discharging fuel oil under high pressure from a suitable spray nozzle, comprising a pump body in which is formed a pump chamber, a plunger mounted in said body and extending into said chamber, said plunger being normally retained in a raised position, means permitting of the sudden downward movement of the plunger to admit oil into said chamber and for successively moving said plunger upwardly to displace the oil previously admitted to said chamber in the downward movement of said plunger, said means involving a cam, a plurality of levers disposed between the cam and the plunger, two of said levers having substantially oppositely disposed fulcrums, and the other of said levers being disposed between the first named levers and adapted to control and regulate the movement imparted to said plunger.

7. A pump mechanism for discharging fuel oil under high pressure from a suitable spray

nozzle, comprising a pump body in which is formed a pump chamber, a plunger mounted in said body and extending into said chamber, said plunger being normally retained in a raised position, means permitting of the sudden downward movement of the plunger to admit oil into said chamber and for successively moving said plunger upwardly to displace the oil previously admitted to said chamber in the downward movement of said plunger, said means involving a cam, a plurality of levers disposed between the cam and the plunger, two of said levers having substantially oppositely disposed fulcrums, the other of said levers being disposed between the first named levers and adapted to control and regulate the movement imparted to said plunger, and automatically operated means for imparting movement to said last named lever.

8. A pump mechanism for discharging fuel oil under high pressure from a suitable spray nozzle comprising a pump body in which is formed a pump chamber, a plunger mounted in said body and extending into said chamber, means involving a cam and a plurality of levers disposed between the cam and said plunger for actuating said plunger whereby in one cycle of the cam action, the plunger will be retained in a raised position in said chamber through substantially three quarters of such cycle of operation and whereby in substantially the other quarter of the cycle of operation, said plunger is given sudden downward movement to admit oil into said chamber and successive upward movement to displace the oil admitted into said chamber in the downward movement of the plunger.

9. A pump mechanism for discharging fuel oil under high pressure from a suitable spray nozzle, comprising a pump body in which is formed a pump chamber, a plunger mounted in said body and extending into said chamber, means involving a cam and a plurality of levers disposed between the cam and said

plunger for actuating said plunger whereby in one cycle of the cam action, the plunger will be retained in a raised position in said chamber through substantially three quarters of such cycle of operation and whereby in substantially the other quarter of the cycle of operation, said plunger is given sudden downward movement to admit oil into said chamber and successive upward movement to displace the oil admitted into said chamber in the downward movement of the plunger, and automatically operated means for imparting movement to one of said levers to control and regulate the movement imparted to said plunger.

10. A pump mechanism for discharging fuel oil under high pressure from a suitable spray nozzle, comprising a pump body in which is formed a pump chamber, means for supplying oil to said chamber and a discharge pipe in communication with said chamber, a plunger mounted in said body and extending into said chamber, means involving a cam and a plurality of levers disposed between the cam and said plunger for actuating said plunger whereby in one cycle of the cam action, the plunger will be retained in a raised position in said chamber through substantially three quarters of such cycle of operation and whereby in substantially the other quarter of the cycle of operation, said plunger is given sudden downward movement to admit oil into said chamber and successive upward movement to displace the oil admitted into said chamber in the downward movement of the plunger, automatically operated means for imparting movement to one of said levers to control and regulate the movement imparted to said plunger, and check valves in said supply means and said discharge pipe.

In testimony that I claim the foregoing as my invention I have signed my name this 23rd day of July, 1923.

CARL H. KNUDSEN.
